UNITED STATES PATENT OFFICE.

NORMAN I. EDWARDS, OF LONGUEUIL, QUEBEC, CANADA, ASSIGNOR TO FRANKLIN
RAILWAY SUPPLY COMPANY, A CORPORATION OF DELAWARE.

DRIVING-BOX WEDGE ADJUSTMENT.

Application filed December 5, 1924. Serial No. 754,044.

To all whom it may concern:

Be it known that I, NORMAN I. EDWARDS, a subject of the King of Great Britain, residing at Longueuil, in the Province of Quebec, Canada, have invented certain new and useful Improvements in Driving-Box Wedge Adjustments, of which the following is a specification.

This invention relates to driving boxes, and particularly to that form of box in which automatic compensating wedges are used, such for example as are employed in locomotives.

One of the primary objects of my invention is to provide simple and durable means for actuating the compensating wedge. A further object is to provide easily accessible adjustment for the actuating means; to provide means to lock said adjusting mechanism in position; and to prevent maladjustment of the actuating means.

These, together with such other objects as may hereinafter appear, or are incident to my invention, I obtain by means of a construction illustrated in the accompanying drawings, wherein.

Fig. 1 is a side elevation and partial section of a driving box illustrating the application of my improved actuating and adjusting means thereto;

Fig. 2 is a section through the actuating and adjusting mechanism which is shown on a larger scale than in Fig. 1;

Fig. 3 is a plan view of the supporting bracket;

Fig. 4 is a plan view of an adjusting nut; and

Fig. 5 shows a detail of the construction.

Referring now to the drawings, the reference letter A indicates the main frame of a locomotive with pedestal jaws 5 and 6, in which the driving box B is mounted for vertical movement.

Upon the pedestal faces of the driving box B are the driving box gib 7 and interposed between the gib 7 on one side and the pedestal jaw 5 are the compensating wedges 8 and 9 which automatically take up any wear caused by the vertical movement of the driving box in the pedestal in a manner well understood in the art. To the wedge member 9 is connected the wedge bolt 10 which extends down through the pedestal

binder 11 and projects therebelow. The lower end of this bolt 10 is screw threaded. 55

Just below the bolt hole in the binder 11 is the bracket or yoke 12 which is secured to the binder by means of the bolts 13. The bottom of this bracket 12 is provided with an opening 14 and also has, on the inner 60 face the grooves or indentations 15, into which corresponding projections 16 on the plate or washer 17 are adapted to fit. Surrounding the bolt 10 and resting on the plate or washer 17 is placed the spring 18. 65 The upper end of this spring bears against a shoulder 19 of the tubular nut member 20.

This member 20 is of a hexagonal shape (see Fig. 5), internally shouldered and threaded at its upper end and adapted to 70 be screwed onto the wedge bolt 10. The lower portion projects through the opening 14 beyond the lower part of the bracket 12 where it can be readily gripped by a wrench and turned to adjust the tension on the 75 spring 18, which, acting through the member 20 and bolt 10 pushes the wedge 9 home.

The washer 17 has a hexagonal opening which engages the hexagonal member 20. When the member 20 is turned to effect adjustment of the tension of the spring this washer 17 turns with it, the projection 16 rising out of the grooves 15 in the bottom of the bracket and sliding over the inner surface of the bracket until a quarter turn has 85 been made when the projections snap back into the grooves.

This arrangement of the grooves and projections prevents complete compression of the spring 18 for if the spring be compressed, or almost compressed, when the projections on the washer 17 are out of the grooves 15 in the bottom of the bracket, a further turning of the member 20 to cause the projections 16 to snap back into the 95 grooves 15 will thereby release the spring to an amount corresponding to the height of the projections 16 on the washer. It will thus be seen that the spring can never be compressed solid unless the grooves and projections are out of their proper position.

A further purpose of this arrangement of grooves and projections is to lock the parts in position when they have been adjusted. When the projections 16 register with the 105 grooves 15 the tension of the spring 18 will

hold the washer in position, preventing it from turning accidentally. This washer in turn will prevent the nut 20 from turning and working up on the bolt 10 to release the 5 spring tension.

It will be seen that I have provided a simple and efficient adjustable wedge mechanism in which the parts are easily accessible for adjustment and in which it is practically 10 impossible to make any adjustment which would cause jamming of the wedge so as to interfere with the vertical movement of the driving box.

I claim:

15 1. The combination with a frame and driving box mounted therein, of a wedge, means for yieldingly pressing the wedge into engagement comprising a bolt, a spring, a support for the spring and a nut member on the bolt engaging said spring and projecting through said support.

20 2. The combination with a frame and driving box mounted therein, of a wedge, means for yieldingly pressing the wedge into engagement comprising a bolt, a spring, a support for the spring and a nut member on the bolt engaging said spring and extending between said spring and bolt and projecting beyond the support.

25 3. The combination with a frame and driving box mounted therein, of a wedge, means for yieldingly pressing the wedge

into engagement comprising a bolt, a spring, a support for the spring having grooves 35 therein, a nut member on the bolt engaging the spring, a washer interposed between said spring and said support and having projection adapted to fit into said grooves, said washer fitting about said nut and turning therewith.

40 4. The combination with a frame and driving box mounted therein, of a wedge, means for yieldingly pressing the wedge into engagement comprising a bolt, a spring, a support for the spring having grooves 45 therein, a nut member on the bolt engaging the spring, means engaging said nut and interposed between said spring and said support and having projections adapted to fit into the grooves of the support to lock the 50 nut against unintended turning.

45 5. The combination with a frame and driving box mounted therein, of a wedge, means for yieldingly pressing the wedge into engagement comprising a bolt, a coil spring 55 around said bolt, a seat member for said spring, and an adjusting nut on the bolt against which the spring bears, said seat having an opening and said nut extending within said spring and through said 60 opening.

In testimony whereof, I have hereunto signed my name.

NORMAN I. EDWARDS.
